UNITED STATES PATENT OFFICE

172,272

TOY DOG OR SIMILAR ARTICLE

Pleas A. Ewing, Nashville, Tenn., assignor to Kusan Incorporated, Nashville, Tenn.

Application February 26, 1954, Serial No. 29,222

Term of patent 7 years

(Cl. D34—2)

To all whom it may concern:

Be it known that I, Pleas A. Ewing, a citizen of the United States, residing at Nashville, State of Tennessee, have invented a new, original, and ornamental Design for A Toy Dog or Similar Article, of which the following is a specification, reference being had to the accompanying drawing, forming a part hereof.

I claim:

The ornamental design for a toy dog or similar article, as shown.
